UNITED STATES PATENT OFFICE.

EDWARD R. E. COWELL, OF DETROIT, MICHIGAN, ASSIGNOR OF THREE-FOURTHS TO WILLIAM DE WAGGSTAFF, OF RUSSIA.

SPEED-INDICATOR.

SPECIFICATION forming part of Letters Patent No. 296,679, dated April 8, 1884.

Application filed December 12, 1883. (No model.)

To all whom it may concern:

Be it known that I, EDWARD R. E. COWELL, of Detroit, in the county of Wayne and State of Michigan, have invented new and useful Improvements in Speed-Indicators; and I do hereby declare that the following is a full, clear, and exact description thereof, reference being had to the accompanying drawings, which form a part of this specification.

10 This invention relates to certain new and useful improvements in the construction and operation of devices by means of which the speed of a railway-train may be indicated to the engineer or conductor.

15 The invention consists in the peculiar arrangement and construction of the several parts, all as more fully hereinafter set forth.

Figure 1 is a sectional elevation of my invention, and Fig. 2 is a section on the line $\times \times$ 20 of Fig. 1.

In the accompanying drawings, which form a part of this specification, A represents the axle of the forward truck of a locomotive, upon which is rigidly secured or formed the worm 25 B, designed to engage with the pinion C upon the shaft D, which has bearings in the side walls of the casing E E', pendent from the truck and embracing the axle, the parts being so arranged that the said worm and pinion are at 30 all times in engagement. The casing is made up of two parts, E and E', the former being secured to the bottom of the truck, and having the shield or guard e cast integral therewith, which incloses the pinion C on its forward side, except at its lower end, where it meshes with the worm B. The part E' is secured to E by bolts passing through the same on either side of the axle. The counter-shaft D, which carries the pinion C, is mounted between the two 40 parts E and E', and has the flexible shaft F secured to its outer end. It will be noticed that the part E performs a double office—that of strengthening the axle A at the parts a, where it is cut away, and also supports the 45 counter-shaft D. The guard e prevents all sand, grit, and such like foreign matter from getting onto the wearing parts of the worm and pinion.

F is a flexible shafting, one end of which is 50 secured to one end of the shaft D, while the opposite end is connected to the upper end of

the shaft H, journaled vertically in the casing I, which is located at any convenient point within the locomotive-cab. Rising from the casing I and stepped in an offset tube, I', is a 55 glass tube, K, provided with an index showing speed in miles, and upon the shaft H, I secure a screw or propeller wheel, G, which rotates in oil J, or other resistance-fluid with which the casing is filled.

In practice, the movement of the locomotive through the connections herein named imparts a rotary motion to the propeller-wheel G, and the power developed by this wheel tends to to force the oil up the tube, the height of the 65 oil in the tube indicating to the engineer the rate of speed at which his engine is being driven, the gravity of the oil acting as a counter-balance. If the top of the tube K be closed, I have an additional resistance in the compression of the air within the tube.

I consider it important that the casing should be provided with an offset tube, as it affords an easy means for securing the graduated tube to said casing, besides forming a separate chamber, the opening of which is in the same plane as the wheel G. The bottom of said offset, curving upward, guides the fluid more easily in its ascent. As the liquid in both chambers of the casing will be on a level when the vehicle is at 80 rest, a very slow movement of the propeller, with my construction and arrangement of parts, will cause the liquid to be displaced and rise in the graduated tube. Another novel feature is the flexible connection between the motive 85 power and the indicator, said connection being directly attached to the propeller-shaft and to the counter-shaft, deriving its motion from the main shaft, said construction admitting of the indicator being placed in a variety of positions, as occasion may require.

I am aware of the Patent No. 153,470, and make no claim to the construction shown therein, as I deem my invention as essentially different therefrom and an improvement thereon, inasmuch as my bracket E supports and strengthens the axle at a point where strength is most needed, while in the above-mentioned patent the axle is in no way supported by the bracket, but is forced to carry the bracket and shaft and help to support the gearing carried by said shaft, and connections running from

said axle to the speed-indicator, besides having to sustain the strain which is incident to lateral and forward lunges of the gearing caused by the same being loosely supported.

5 What I claim as my invention is—

In a speed-indicator, the combination of the axle A, carrying the worm B, the pendent bracket E, secured to the under side of the truck and supporting said axle and strengthening the same at a, the shaft D, supported at one end by the bracket E, and at the other by the part E, attached to the bracket E, which has the shield

e cast integral therewith, pinion C, carried by said shaft D, and inclosed within the casing E E', and meshing with the worm B, and the flexible shaft F, attached at one end to the shaft D, and at its other end to the indicator, substantially as and for the purpose described. 15

EDWARD R. E. COWELL.
